(57) **CLAIM**

We claim the ornamental design for a toy vehicle, as shown and described.

DESCRIPTION

FIG. 1 shows a top front right perspective view of a toy vehicle.

FIG. 2 shows a top rear left perspective view of the toy vehicle of FIG. 1.

FIG. 3 shows a right side view of the toy vehicle of FIG. 1.

FIG. 4 shows a left side view of the toy vehicle of FIG. 1.

FIG. 5 shows a front view of the toy vehicle of FIG. 1.

FIG. 6 shows a rear view of the toy vehicle of FIG. 1.

FIG. 7 shows a top view of the toy vehicle of FIG. 1.

FIG. 8 shows a bottom view of the toy vehicle of FIG. 1.

FIG. 9 shows a top front right perspective view of an alternative embodiment of a toy vehicle.

FIG. 10 shows a top rear left perspective view of the toy vehicle of FIG. 9.

FIG. 11 shows a right side view of the toy vehicle of FIG. 9.

FIG. 12 shows a left side view of the toy vehicle of FIG. 9.

FIG. 13 shows a front view of the toy vehicle of FIG. 9.

FIG. 14 shows a rear view of the toy vehicle of FIG. 9.

FIG. 15 shows a top view of the toy vehicle of FIG. 9; and,

FIG. 16 shows a bottom view of the toy vehicle of FIG. 9.

The broken lines shown in the drawings illustrate portions of the toy vehicle that form no part of the claimed design.

1 Claim, 6 Drawing Sheets
